DOUBLE TWIST TWISTING SPINDLE

Otto Bochmann, Remscheid-Lennep, Germany,
assignor to Barmer Maschinenfabrik Aktiengesellschaft, Wuppertal-Barmen, Germany

Application March 3, 1938, Serial No. 193,656
In Germany March 22, 1937

5 Claims. (Cl. 57—58)

This invention relates to a double twist twisting spindle, in which the upper part of the spindle, consisting of a thread take-up disc and of a hollow spindle, is rigidly connected with the lower part of the spindle, and in which the thread coming from the supply spools is drawn through a guide passage by means of a threading wire. The thread coming from the stationary supply spool and passing out under the thread take-up disc is then conducted over the thread guide to the winding spool. The known spindles of this type are, however, open to the disadvantage that the hollow twisting spindle or the passage for the running off thread has its outlet only at a point of the wharve below the thread guide or below the thread take-up disc. On this account not only the cutting of the thread into the material is greatly facilitated, as the thread always runs through one and the same passage but this construction makes the operation much more difficult. The first mentioned disadvantage is always present as after the stopping and refilling of the spindle the threads must be threaded through the spindle with the aid of a threading wire. In this instance the attendant is always obliged to look for the inlet hole for introducing the threading wire and to turn the spindle by hand for this purpose. Heretofore, the spindle being held stationary by a brake, the brake must be disengaged after the machine has come to a standstill to enable the spindle to be turned. The operation is therefore inconvenient and wastes time, quite apart from the fact that for stopping the spindle specially equipped braking devices are necessary which allow the above mentioned procedure. Another disadvantage of the known spindles of this type is that the spindle shank is guided along its whole length so that the bore in the spindle must pass out laterally. This, however, makes the production more difficult and expensive. It has already been proposed to guide the spindle in a curve and allow it to deliver below the thread guide body. This, however, is open to the objection that it is very difficult to make the spindle shank run true apart from the fact that in this instance the wharve and thread guide body must be made of a certain material.

A double twist twisting spindle is known in which two diametrically opposite passages leading outwards are provided for the thread. However, these two passages only serve for avoiding the impetus moments within the spindle. Furthermore, this construction also possesses the above mentioned disadvantages as two diamet-

rically opposite passages do not yet ensure that, when the spindle has been stopped, one passage will be directed towards the front for threading the thread. Moreover, there is also the danger of the thread cutting into the material as threading the thread through one and the same passage is easier. Furthermore, it has become known from another double twist twisting spindle to provide several thread outlets within the thread take-up disc, but in this instance the construction is absolutely different. In this spindle the upper part proper of the spindle consisting of the thread take-up disc, thread guide body and hollow spindle, is taken off the direct twisting spindle. Thus, in this instance the thread is not threaded at all on the spindle so that there are no separate threading passages, but the thread is previously pulled downwards so that, when the upper part of the spindle has been placed on the twisting spindle, the thread passes between the upper and lower parts of the spindle.

The object of the present invention is to eliminate the above mentioned disadvantages. According to the invention several passages are provided for the thread on the entire periphery of the wharve or of the take-up disc made in one piece with the wharve, said passages converging in upward direction and terminating in the hollow spindle. These passages may be of round or slot shaped cross section. It is advisable for the transition of the thread from the hollow spindle to the passages to allow the hollow spindle to project, whereas for the transition from the passages to the take-up disc a slightly projecting steel wire is arranged so that the thread runs freely through every passage, that is without coming into contact with the side walls.

This construction possesses the advantage that a cutting of the thread into the material need no longer be feared as the thread not always runs through one and the same passage but changes the passage when threaded again. Another advantage consists in the greatly facilitated attendance as the spindle need not be turned for the threading of the thread, or the threading hole need not be found for threading the wire. When the spindle is stopped always one of the passages is directed towards the front so that the attendant can immediately carry out the threading of the thread without difficulty. However, this at the same time results in a simpler construction of the braking device, as it is no longer necessary to turn the spindle by

hand. Furthermore, the manufacture is considerably simplified and cheapened as only a short spindle shank is employed, which has a smooth continuous bore. It is also possible by this form of construction to make the main parts of the spindle of artificial resin thereby greatly simplifying and cheapening the cost of production.

Two embodiments of the invention are illustrated by way of example in the accompanying drawings, in which:

Fig. 1 shows a double twist twisting spindle in longitudinal section,

Fig. 2 is a cross section on line II—II of Fig. 1,
Fig. 3 shows in longitudinal section a modified form of construction,

Fig. 4 is a cross section on line IV—IV of Fig. 3.

According to Figs. 1 and 2 the wharve 1 and the take-up disc 2 are made in one piece and have several slot-shaped passages 3 which converge in upward direction and end below the take-up disc 2. The bore in the hollow spindle 4 forms extensions of these passages 3 and the spindle which is only short is held in the upper part of the wharve. 5 is a stationary thread guide body. The thread is threaded through one of the passages 3 with the aid of a threading wire and pulled out at the lower end of the passage. The short spindle 4 or the lower outlet of the bore in the spindle projects slightly and at the transition point between the passages 3 and the thread take-up disc 2 a projecting steel wire 6 is provided so that the thread can run freely through every passage. Another spindle 7 is fixed in the lower part of the wharve.

Figs. 3 and 4 show a similar spindle 4a carrying a thread guide 5a only with the difference that here the upwardly converging passages 3a do not terminate in the under side of the take-

up disc 2a itself but laterally of the wharve 1a, and are of round cross section. Furthermore, in this construction the spindle 7a serving as mounting is constructed as a stationary bolt on which the wharve is mounted by means of ball bearings 8a. In this example the thread passes through the hollow spindle 4 and through one of the passages 3a over the take-up disc 2a and thread guide 5a to the winding spindle 4a. In this construction a wire 6a also projects slightly into the passages 3a at the outlet end thereof.

I claim:

1. A double twist twisting spindle of the type with rigidly connected upper and lower spindle parts, comprising in combination a wharve and a thread take-up disc made in one piece, a short shaft extending from the upper end of said wharve and having a central bore, said wharve having a plurality of thread passages converging upwards from the lower side of said take-up disc and leading into the central bore of said shaft.

2. A double twist twisting spindle as specified in claim 1, in which the inlet apertures of said passages are in the outer wall of the wharve below the take-up disc.

3. A double twist twisting spindle as specified in claim 1, in which the passages are of annular cross-section.

4. A double twist twisting spindle as specified in claim 1, in which the passages are of slot-shaped cross section.

5. A double twist twisting spindle as specified in claim 1, in which the spindle shaft projects at the point at which it communicates with the passages, and a steel wire is fitted at the point of transition between the passages and the take-up disc.

OTTO BOCHMANN. 40
